APPARATUS FOR HEATING FLUIDS

John S. Wallis, Darien, and John W. Throckmorton, Wilton, Conn., assignors to Petro-Chem Process Company Incorporated, a corporation of Delaware

Application January 18, 1943, Serial No. 472,676

3 Claims. (Cl. 122—356)

Our invention relates to improvements in heaters and refers more particularly to a heater in which a fluid is passed through a heating chamber in a plurality of separate streams in order to heat the fluid rapidly to a predetermined temperature, the design being such that not only is the temperature of the fluid rapidly and uniformly attained but provision is also made for cooling or quenching the fluid when a given time period of heating has elapsed.

In the treatment of fluids, particularly in the petroleum and chemical industries, there is at the present time an insistent demand for a heater in which fluids may be rapidly raised to a high temperature (1000° to 15000° F.) and a heater in which such temperatures can be maintained for a predetermined period of time. Such requirements are not satisfied by a single coil in which the fluid is passed in a stream through a heating zone as the rate of heat exchange between the combustion gases and fluid medium is not sufficiently rapid to attain the desired temperature within the time period allowed, due to the difficulties in exposing sufficient surface of the fluid to the heating gases.

In the heating of hydrocarbons or similar materials for the production of chemical products, with or without the use of catalyst when temperatures are in excess of 1000° F., the relationship between the heating surface, the reaction time and the heat transfer rates all become important and critical factors. Such reactions generally require minimum time under temperature, which necessitates the use of small tubes, low pressure drop, high transfer rate, and a multiplicity of passes through the heating zone. In addition, it is advantageous, in some instances, to reduce the temperature as quickly as possible upon discharge from the heating zone.

For example, a furnace employing 4" tubes as compared with a furnace having double the number of 2" tubes has approximately the same heating surface, but the volume or time of reaction is reduced by one-half.

Our invention provides a heater having a plurality of passes of small diameter heat exchange tubes so disposed that each pass absorbs the same amount of heat. It also becomes important, in some types of processing, to reduce the temperature of materials being heated immediately upon reaching a predetermined temperature, so that the materials being heated are subjected to a rising temperature gradient from the inlet to the point where the temperature is arrested.

In other cases, the location of the temperature

reduction or arresting zones may be more remote from the tube outlets, giving a longer time period before temperature quenching.

Our heater construction is designed to satisfy these requirements.

In the accompanying drawings which form a part of the instant specification and are to be read in conjunction therewith and in which reference numerals are used to indicate like parts in the various views,

Fig. 1 is a sectional elevational view,

Fig. 2 shows a developed section of the tubular heating elements,

Fig. 3 is a view taken along the line 3—3 in Fig. 1 in the direction of the arrows,

Fig. 4 is a view taken along the line 4—4 in Fig. 1 in the direction of the arrows,

Fig. 5 is an elevational view of a modified type of heater with parts broken away,

Fig. 6 is a view taken along the line 6—6 in Fig. 5 in the direction of the arrows, and

Fig. 7 is a view taken in the same location showing two streams of the heater connected by means of a Y connection prior to being discharged in the accumulator.

Referring to the drawings, in Figs. 1 and 5 the outer shell combustion chamber and flue construction are substantially the same. It consists of a vertical casing 10 lined with insulation 11 and fire resistant lining such as silocel, carborundum, brick or other type of fire resistant material shown at 12. The chamber is fired by directional burners diagrammatically shown at 13. The heater is supported on suitable standards 30 or legs shown at 14. In the upper part of the combustion chamber is a baffle 15 which diverts the combustion gases outwardly near the top of the heater and increases the heat exchange between the cooler combustion gases and the tubes 35 in that section of the heater. On the upper portion of the tubes adjacent the baffle and where the tubes are subjected principally to convection heat, extended surfaces may be used although this detail has been omitted from the drawings 40 in the interest of simplicity.

The novelty of the construction lies principally in the arrangement of the tube sections within a cylindrical heater and the manner in which they are connected to the inlet and outlet manifolds. The construction details of the heating chamber are of secondary importance. At the top of the heater is a breeching 16 surmounted by a chimney or stack 17.

In both types of construction shown in Figs. 1 and 5 near the top of the heater is a circular

manifold 18 to which fluid may be introduced through pipes 19. The number of these inlet pipes will depend upon the size of the heater and the rate at which it is desired to introduce fluid to the tubes. Within the cylindrical heating chamber and arranged around the inside surface or wall 12 are a plurality of vertical tube sections 20. The one extremity of each tube section is connected to the manifold 18, as shown in Fig. 2. Each of the tube sections consists of a plurality of vertical passes joined by return bends, as shown in Fig. 2.

In the construction shown in Figs. 1 to 4, inclusive, the opposite ends of the individual tube sections from those connected to the manifold 18 are joined to a bottom manifold 21. Outlet pipes 22 are connected to this bottom manifold to draw off the heated liquids. These outlet or withdrawal pipes may be located at any suitable points around the periphery of manifold 21. At intervals on the circumference of the lower manifold or above the manifold where the tube sections leave the heating chamber are connected inlet pipes 23, as shown in Figs. 2 and 4, which provide means for introducing a cooling or quenching fluid to the fluid being heated. In the modified construction shown in Figs. 5 and 6 in place of a lower circular manifold 21 an accumulator or tank 24 is used. Into this accumulator are connected the discharge ends of the separate tube sections. A cooling or quenching fluid may be introduced to the accumulator through pipe 25 and in the event that a single pipe is insufficient to supply an adequate amount of cooling fluid, a plurality of pipes may be used. Discharge from the accumulator is through pipe 26. In the modification shown in Fig. 7 the discharges from two of the tube sections 20 are combined in a single pipe which flows into the accumulator 24. By this modification the fluid from two of the pipe sections is combined before entering the accumulator.

The flow of fluid through the heater shown in Figs. 1 to 4, inclusive, would be as follows: Fluid to be heated is introduced through inlet pipes 19 connected to manifold 18. This manifold or distributor directs the fluid to the individual tube sections 20 through which the fluid is circulated through the heating space within the furnace. During its passage through tubes 20 the fluid is subjected to both radiant and convection heat and the temperature rapidly brought to the desired point. The fluid is discharged into the lower manifold 21 from which it may be withdrawn. When cooling or quenching of the heated fluid is desired cooling fluid is introduced through pipes 23 above the manifold 21 or through pipes designated by the same number connected into the manifold.

In the construction shown in Figs. 5 to 7, inclusive, fluid introduced through pipes 19 passes through manifold 18 down through the separate tube sections 20 from which it is discharged into an accumulator 24. From the accumulator it is withdrawn through pipe 26 either in highly heated form or in cooled condition due to mixture with the cooling fluid introduced to the accumulator through pipe 25.

As an indication of the wide difference in results obtained by varying the furnace design, the length of travel of the fluid during heating, the time of cooling or quenching and other critical factors related thereto, we offer the following typical example:

When petroleum naphtha was heated to 1350° 75

F. in 2" tubes in a heater of our design there was obtained a conversion rate of substantially 20% and by cooling the fluid immediately at the furnace outlet a material of definite composition was recovered. When the same charging stock was used and 4" tubes having the same heating surface were employed in a furnace of the same design there was obtained approximately 40% conversion, giving a resultant material of entirely different composition.

A further variance of the composition of the product is produced by the location of the temperature quenching point.

In the foregoing it will be seen that our invention is one well adapted to attain the ends and objects hereinbefore set forth, together with other advantages which are obvious and which are inherent to the structure.

It will be understood that certain features and sub-combinations are of utility and may be employed without reference to other features and sub-combinations. This contemplated by and is within the scope of our claims. It is further obvious that various changes may be made in details with the scope of our claims without departing from the spirit of our invention. It is therefore to be understood that our invention is not to be limited to the specific details shown and described.

Having thus described our invention, we claim:

1. A heater construction comprising a cylindrical combustion chamber, a heat source within said chamber, vertical tube banks located adjacent the combustion chamber wall having inlet and outlet ends, an inlet distributor at the top and outside of the combustion chamber and an outlet accumulator, in the bottom, and located outside the combustion chamber said inlet ends connected to the distributor and said outlet ends connected to the accumulator, means for introducing fluid into said distributor, means for withdrawing heated fluids from said accumulator and means for introducing a quenching medium adjacent the outlet ends of said tube banks.

45 2. A heater construction comprising a cylindrical combustion chamber, a heat source within said chamber, vertical tube banks located adjacent the combustion chamber wall having inlet and outlet ends, an inlet distributor at the top and outside of the combustion chamber and an outlet accumulator, in the bottom, and located outside the combustion chamber said inlet ends connected to the distributor and said outlet ends connected to the accumulator, means for introducing fluid into said distributor, means for withdrawing heated fluids from said accumulator, and means for introducing a quenching medium to the accumulator.

60 3. A heater construction comprising a cylindrical combustion chamber, a heat source within said chamber, vertical tube banks located adjacent the combustion chamber wall having inlet and outlet ends, an inlet distributor at the top and outside of the combustion chamber and an outlet accumulator, in the bottom, and located outside the combustion chamber, said inlet ends connected to the distributor and said outlet ends connected to the accumulator, means for introducing fluid into said distributor, means for withdrawing heated fluids from said accumulator, and means for introducing a quenching medium into the outlet ends of each tube bank ahead of their connection to the accumulator.

JOHN S. WALLIS.
